ABSTRACT: An oscillating power unit for use with a variety of tools and equipment that are vibrated in their operation. An inertial mass rocking about a fixed pivot is driven by an orbital motion eccentric mechanism in such a manner that the effective power is concentrated along one axis of motion and minimized in all other directions. The eccentric drive has a variable throw that is easily adjusted to selectively vary the oscillating power output when the unit is installed in an operating assembly without dismantling the structure, although all moving parts except the drive shaft are fully enclosed.

OSCILLATING POWER UNIT

BACKGROUND OF THE INVENTION

Vibrators, oscillating power devices and other such devices, used on a variety of tools and machines, such as rock crushers, digging and boring apparatus, rippers, and the like, generally incorporate some type of inertial mass that is rotated or swung about an axis to generate a reciprocating power force. These mechanisms are normally designed so that the greatest effective power occurs in given directions, but unwanted forces also occur in other directions and the mechanisms must either be limited in maximum power output or be designed with excess strength to withstand the loads. Even where the mechanisms are designed to withstand the loads, the devices to which they are attached often cannot withstand the excessive forces. Some vibrators have used dual inertial masses that are synchronized to work together in one direction and oppose each other in other directions. These are cumbersome for the power developed and they do not entirely solve the problem. Furthermore, the power output of such vibrators is usually difficult or impossible to adjust without dismantling the apparatus, and the speed or pulse rate is often the only reasonably, adjustable variable.

Thus it is advantageous to have an oscillating power unit that is capable of providing large oscillating or reciprocating power output from a compact unit, which power output is easily controlled.

SUMMARY OF THE INVENTION

In an illustrative embodiment of this invention, the oscillating power unit has an inertial mass oscillator mounted for a rocking action in the plane of useful power output, and is driven by an orbital eccentric mechanism in such a manner that maximum power is produced along one axis and force moments in other directions are minimized. All moving parts except an extending drive shaft are fully enclosed in a compact casing and the unit is readily adaptable to various tools and machines requiring a controlled vibratory action. In addition to speed control, the power output is also adjustable by varying the eccentric stroke. This is easily accomplished through conveniently located access in the casing, without dismantling the unit or disturbing its mounting.

The orbital eccentric mechanism has means for translating rotation of a drive shaft to reciprocating, linear pivotal movement of the eccentric mechanism within the inertial mass, that moves the oscillator mass in a reciprocating, rocking, movement about a fixed offset pivot. The internal forces between the eccentric mechanism and the oscillator mass in translating force from the shaft to the oscillator mass, creates reciprocating force moments along a given axis, and absorbs force moments in other directions. The amount of force generated is selectively set by rotatably positioning one eccentric member within another eccentric member within the eccentric mechanism. This allows selective setting of the throw of the eccentric mechanism and the rocking movement of the oscillator and thus selective setting of the oscillating force generated.

It is therefore an object of this invention to provide a new and improved oscillating power unit.

Other objects and many advantages of this invention will become more apparent in reading the following detailed description wherein like reference numerals designate like parts throughout and in which:

FIG. 1 is a side elevation of an embodiment of the invention.

FIG. 2 is an illustration of a typical use of an embodiment of the invention.

FIG. 3 is an enlarged sectional view taken on line 3-3 of FIG. 1.

FIG. 4 is a sectional view taken on line 4-4 of FIG. 3.

FIG. 5 is a sectional view taken on line 5-5 of FIG. 4.

FIG. 6a to 6c show three different adjustments of eccentric throw in diagrammatic form.

FIGS. 7a to 7f are diagrams of six positions of the mechanism through one complete cycle of operation.

The power unit is contained in a cylindrical casing 10 enclosed by end plates 12 and mounted on a base frame 14 for convenience of attachment to various apparatus by any known suitable means. As illustrated, the frame 14 comprises a base plate 16 and a pair of arcuate saddle members 18 in which casing 10 is seated, but the configuration may vary according to specific use.

10 Inside casing 10 is a substantially discoid inertial weight element or oscillator 20, that is pivoted near its lower edge on a rocker pin or shaft 22 extending across the casing 10 parallel to the axis of the cylindrical casing. The oscillator 20 is smaller than the interior of casing 10 to allow clearance for a rocking motion and is slightly elongated in a direction radial to pin 22. This minimizes clearance at the top and bottom while allowing sufficient clearance at the sides. In the center of oscillator 20 is a large void opening 24 that is elongated horizontally and extends axially through the complete thickness of the oscillator 20. Fixed in the opposite ends of opening 24 are vertical wear plates 26 with parallel opposed faces. The opposite ends of rocker pin 22 are held in sockets 28 of cap members 30 which are inset in openings in the end plates 12 as illustrated in FIG. 3. The cap members 30 are secured to the end plates 12 by bolts 94 and cap screws 32 close threaded openings through which studs are inserted to facilitate removal of the cap members 30.

Mounted in the opening 24 is a generally avoid slide block 36, with side plates 38 fixed to opposite ends to slide smoothly on wear plates 26. In the center of slide block 36 is a large circular bore 40 containing axially positioned roller bearings 42 with bearing races 43. Mounted in the bearings 42 is an eccentric drive block 44. The drive block 44 is split longitudinally on a vertical plane into two portions designated 44a and 44b, which are connected by axially extending, circumferentially spaced bolts 46. The heads 47 of bolts 46 abut against the opening in portion 44a and the threaded ends 49 engage the portion 44b. The heads 47 have known socket springs 48 retained in opposed sockets 50 between the two drive block portions, as illustrated in FIG. 3. To retain slide block 36 in centered alignment, guide plates 52 are inset in oscillator 20 along opposite ends of wear plates 26, and project inwardly over the ends of slide plates 38.

45 Drive block 44 is driven by a drive shaft 54 extending axially through casing 10, the ends being journaled in suitable bearings 56. The bearings 56 are held in bearing plates which, for purposes of description, are designated front bearing plate 58 and back bearing plate 60, inset in and secured to end plates 12 by bolts 95. In the front bearing plate 58 are set screws 62 that engage and apply axial load to the bearing therein, to eliminate axial play. Drive shaft 54 has an eccentrically enlarged central lobe 64 with tapered cylindrical shoulders 66 and reduced end portions 68. Drive blocks 44a and 44b have eccentrically offset bores 70 shaped to fit closely on the lobe 64 and shoulders 66, so that clamp bolts 46 can be tightened to lock the drive block portions on the tapered shoulders with a jamming action for a positive drive connection.

60 As may be seen in FIGS. 3 and 4, the aligned openings 71 in the drive blocks 44a and 44b are offset from the axis of the drive shaft 54. Thus the upper radial thickness of the drive blocks is greater than the lower radial thickness. Also the center of the enlarged central lobe 64 is offset from the axis of the shaft 54. Since the shaft 54 is rotatable within openings 71, the offset openings 71 and the central lobe 64 form an eccentric positioning of the two masses, which eccentric positioning is adjustable. Such adjustment allows the total mass of the two members, the lobe 64 and the drive blocks 44, and their radial displacement relative to the drive shaft axis to be selectively set, thus providing for selectively setting the throw or strape of the eccentric mechanism. The drive assembly thus comprises an eccentric within an eccentric and is easily adjusted to vary the stroke.

In the front bearing plate 58, are removable access plugs 72 that are spaced to coincide axially with the locations of clamp bolts 46 at a particular position of the eccentric assembly, as illustrated in FIG. 5. To locate this position, an indexing pin 74 is mounted on front bearing plate 58 and is biased by a spring 76 to seat into a radial slot 78 in drive block 44a. Indexing pin 74 has an enlarged head 80 with web portions 82 which normally rest in shallow grooves 84 in a boss 86 projecting from the bearing plate coaxial with the pin. In this position the indexing pin is held clear of slot 78, as in FIG. 3. To lock the eccentric, the pin is turned 90° so that the web portions 82 can drop into deep grooves 88 in boss 86, allowing the pin 74 to enter the slot. With the eccentric so locked and access plugs 72 removed, the clamp bolts 46 are loosened and separator springs 48 push the drive block portions apart. Since pin 74 is secured to end plate 12, the locked pin also holds the drive blocks 44 in the illustrated position. Thus drive shaft 54 can be rotated relative to the drive blocks 44, changing the eccentric relation of lobe 64 to the eccentricity of bores 70. The drive shaft 54 has a slot 57 in the end thereof, which slot may be used to calibrate the position of the two eccentrics and thus the throw or stroke of the oscillator. However other suitable and more precise calibration markings may be used. The slot 78 has a vertical extension to allow for slight vertical movement of the drive blocks 44 that occurs as a result of relative rotational movement between the two eccentrics. At the desired eccentric setting, the clamp bolts are tightened to lock the assembly and the access plugs 72 are replaced and indexing pin 74 is withdrawn and locked out.

To illustrate the changes in throw available, FIGS. 6a, 6b and 6c show three different eccentric positions. A reference marker 90 is used on drive block 44 and a reference marker 92 on lobe 64 to clarify the positions. In FIG. 6a the assembly is set for maximum throw T, with both reference markers radially aligned. In this position, the axial center of shaft 54 is at point 91, the axial center of the assembly is at 93 and the axial center of lobe 64 is at 61. Thus the radial throw of the double eccentric mechanism is the throw T. This represents the distance that the oscillator 20 will be rocked in each direction and also determines the relative up and down and sideward movement of the drive blocks 44, and thus the slide block 36. This maximum throw position is also illustrated in FIGS. 3 and 4. In FIG. 6b, shaft 54 is rotated 90° and the eccentrics are at an intermediate position, with the displacement between center points 91 and 93 giving a reduced throw of T1. FIG. 6c illustrates the markers 90 and 92 substantially opposed with the throw T2 reduced to zero. It may be understood that in this position, the eccentric of the lobe 64 exactly equals the eccentric of the drive blocks 44. Thus the two eccentrics exactly equal each other and the center of the mass and throw 93 is on the axis of the drive shaft 54. Thus rotation of the drive shaft 54 rotates the drive block 44 without imparting rocking motion to the oscillator 20.

The various components are shown as being secured by suitably sized bolts or cap screws 94 with the end plates 12 held in accurate alignment during assembly by dowel pins 96. Specific configurations and assembly details will depend on materials used and the size of the unit.

To provide lubrication of the assembly, the oscillator 20 has oil passages 101 and side oil passages 105, the slide block 36 has oil passages 103 and the bearing races 43 have oil passages 107. In operation, the oil in the unit is normally carried at a level illustrated by dotted lines 111. The oscillator 20, in its rocking movement, drives oil upward through openings 105 and 101 and around the outer surface 113 to the upper space between the oscillator 20 and the slide block 36. The oil then passes through the upper oil holes 101 to the slide block 36 and also flows down the outer surface of the oscillator 20. The slide block 36 in the up and down movement contacts the oil and moves it upwardly through lower holes 103 as well as passing oil through upper holes 103 to the bearings 42 through holes 105. Oil also moves through upper holes 101 and over the outer surface of the slide block 36 to the bearings surfaces

between plates 26, 38 and 52. Pin 22 having oil grooves 34 receives oil through holes 101. The oil may be inserted into the system through the upper valve 109 and hole 107. Valve 109 may be an appropriate pressure set check valve to release pressure buildup or equalize pressure in the internal volume of the oscillating power unit. The oil level 111 is sufficient to provide oil to the rotating drive blocks 44 when the eccentric members are set for zero throw.

The spacing between the surface 115 of the oscillator 20 and the inner surfaces of the end plates 12 is sufficient to pass oil to the bearings 56. Also the surfaces 115 of the oscillator 20 have oil grooves (not shown) to provide controlled oil flow between the adjacent surfaces of the oscillator 20 and the end plates 12. Known seals 49, prevent oil leaks around the drive shaft 54.

OPERATION

In operation, a suitable power source is connected to the drive shaft 54. The eccentric mechanism is then set for the desired amount of throw in the manner previously described. The drive shaft 54 is then rotated, rotating the drive blocks 44 in bearings 42. Since there is an offset of the combination drive lobe 64 and the drive blocks 44, the slide block 36 is moved sideways and up and down. This movement causes the slide block 36 to slide vertically relative to the oscillator 20 and to move the oscillator in a reciprocating, rocking movement around pin 22. This movement is illustrated in FIGS. 7a to 7f, with the drive blocks 44 movement illustrated in 60° increments of clockwise rotation. For reference purposes, the rotation center of axis of drive shaft 54 is indicated by circle 98, with the particular location of the throw of the lobe 64 and drive blocks 44 being indicated by numeral 65.

In FIG. 7a, the eccentric mechanism has the throw in the upward vertical position and the slide block 36 at the top of its stroke. As the drive shaft 54 rotates clockwise, the slide block 36 is moved to the right and downwardly. This pivots the oscillator 20 to the right. As the drive shaft 54 continues to rotate, the slide bearing block and the oscillator 20 moves to the right to the maximum extent for the given eccentric setting. As the slide block 36 moves downward, it also moves back toward the center position pulling the oscillator 20 from the maximum throw to the right. The drive shaft 54 in its rotational movement moves the slide block 36 to the downward position illustrated in FIG. 7d and then continues in movement to the left in the same manner as previously described in the movement to the right. Thus the slide block moves vertically with side movements generally defining a circular movement corresponding to the circular movement of the lobe 64 and drive blocks 44.

The oscillator power unit provides force moments only in substantially the horizontal direction, which is in the direction of arrows 151 and 153. Thus while the slide block 36 has a vertical component of motion, there is almost no vertical oscillation force produced in the unit. In the lateral motion of the mechanism, the inertia of the slide block 36 is added to the inertia of the oscillator 20, the latter being effective about the axis of rocker pin 22 and thus has a long lever arm. The mass of the slide block 36, including the drive blocks 44 and lobe 64, is only a part of the moving assembly and is effective over a smaller lever arm than the whole mass. In addition the energy of the slide block 36 is applied to the weight element through the sliding members 26 and 38, which are inclined to vertical throughout most of the cycle of oscillation. Due to the shallow angle of inclination, as will be apparent in FIGS. 7b, 7c, 7e and 7f the energy of the driven slide block 36 is absorbed in imparting a lateral motion to the oscillator 20. When the slide block mass passes downward through the midpoint of the mechanism, the slide block is exerting force against the oscillator 20 to reverse the rocking movement of the oscillator 20. Thus the vertical force component of the sliding block is absorbed in moving the oscillator 20 and the horizontal throw of the mass provides the horizontal force components.

In apparatus for which the unit is applicable, the component to be vibrated is usually mounted for motion in a particular plane or along a single axis. If the vibrating mechanism has an effect in a direction other than that desired, the structure must be strengthened to withstand the stress which is not always practical. With the present unit such reinforcement is unnecessary. A typical use of the unit is illustrated in simple form in FIG. 2. The complete oscillating power unit 100 is mounted on top of a ripper device having a shank 102 carrying a working tooth 104, or similar ripping structure. The shank 102 is pivotally attached to a frame support 106 to swing from front to rear, as indicated by the directional arrows. The frame has tow bar means 108 for attachment to a vehicle, the power unit being operated as the assembly is towed with the working shank 102 below ground so that the vibration eases penetration. Any suitable motor or power source, not shown, may be used to drive the unit. This is merely one example of use of the oscillating power unit which has many other uses and is not necessarily limited to an upright position as illustrated.

The adjustable throw of the eccentric mechanism makes it possible to control the power output without changing speed, which is an advantage with apparatus having frequency or resonance limitations. Such adjustment can be made as described above without dismantling or removing the unit from the associated apparatus. The rocking action of the oscillator 20 and sliding of the slide block 36 provide effective pumping action to circulate lubricant with the unit. The oil level may be selectively changed to conform, as desired, to different amounts of eccentric throw or vertical movement of the slide block. Because of the compactness and low inertia of the eccentric mechanism itself, the unit is capable of very rapid starting and stopping and the inertia of the oscillator 20 acts as a brake by applying pressure to the slide block when driving power is shut off causing the slide block and power shaft to stop substantially instantly.

Having described my invention, I now claim.

1. An oscillating power unit comprising:

a hollow casing having enclosing end plates thereon,
a drive shaft rotatably mounted in said casing between said
end plates,
a rocker pin fixed in said casing substantially parallel to and
radially offset from said drive shaft,
an oscillatory power generating weight element pivotally
mounted on said rocker pin and enclosing said drive
shaft,
and adjustable throw eccentric drive means coupling said
drive shaft to said weight element.

2. The structure of claim 1 wherein:

said drive means include an eccentric lobe on said drive
shaft,
and a drive block eccentrically mounted on said lobe within
said weight element.

3. The structure of claim 2 wherein:

said weight element has a slide block mounted therein for
sliding motion substantially radial to said rocker pin, said
drive block being rotatably held in said slide block.

4. The structure of claim 3 wherein:

said drive block has clamp means adjustably securing it to
said drive shaft.

5. The structure of claim 3 wherein:

said lobe has axially tapered portions, said drive block being
in two axially separated elements seating on said tapered
portions with clamp means securing the separated ele-
ments together.

6. The structure of claim 5 wherein:

one of said end plates has removable elements exposing said
clamp means.

7. The structure of claim 6 including:

indexing means on said casing, selectively engageable with
said drive block in one position in which said clamp
means are aligned with said removable elements.

5
8. An oscillating power unit comprising:
an oscillator pivotally supported at one side for radial
rocking movement around the pivot,
said oscillator having a rotatable eccentric means posi-
tioned within said oscillator and enclosed thereby and
spaced radially from said pivot for providing an orbital
movement with a rotating eccentric throw,
and said eccentric means has a linear sliding drive connec-
tions with said oscillator and within said oscillator for
translating said orbital movement to reciprocating, radial
rocking movement of said oscillator on said pivot.

10
9. An oscillating power unit as claimed in claim 8 in which:
said eccentric means and said pivot each have an axis of
rotation, which are parallel and are in the same plane.
15
10 An oscillating power unit as claimed in claim 9 in which:
said oscillator has an opening with opposite linear sides,
said sides are parallel with said plane,
and an open space between the upper and lower edges of
20
said eccentric means and said oscillator opening allowing
linear movement of said eccentric means in said oscillator
opening.

11. An oscillating power unit as claimed in claim 10 in
which:
25
said eccentric means has a body with a pair of sides for
slidably contacting said sides in said opening,
said body has a circular opening with a cylindrical member
rotatably positioned therein,
and drive shaft means for rotating said cylindrical member
having an axis of rotation offset from the axis of said
30
cylindrical member.

12. An oscillating power unit as claimed in claim 11 in
which:
35
said drive shaft means includes a drive shaft with an en-
larged cylindrical lobe, the axis of which is offset from the
axis of said drive shaft,
said lobe is rotatable in said body,
and means for fixing said cylindrical member to said lobe at
given rotational positions therebetween, whereby the ec-
centric throw of said lobe may be selectively adjusted.

13. An oscillating power unit as claimed in claim 12 in
which:
the axis of said cylindrical opening in said cylindrical
member is offset from the axis of said cylindrical member.

14. An oscillating power unit as claimed in claim 13 in
which:
said oscillator has a cylindrical shape with flat end surfaces,
a frame for supporting said pivot having flat ends adjacent
said flat ends surfaces and a housing having a cylindrical
opening for enclosing said oscillator,
and said oscillator having oil passages through to said open-
ing at the top and bottom thereof.

15. An oscillating power unit as claimed in claim 13 in
which:
55
said cylindrical member having at least two separable,
axial parts for fitting against the axial ends of said lobe,
and clamp means for drawing said parts axially to a fixed
position against said lobe.

16. An oscillating power unit as claimed in claim 15 in
which:
60
said cylindrical member having means for separating said
separable parts upon releasing said clamp means.

17. An oscillating power unit as claimed in claim 14 in
which:
65
said flat ends of said frame having means for supporting said
drive shaft,
said cylindrical member has a radial slot in the surface ad-
jacent one of said flat ends,
and releasable pin means in said one of said flat ends for
selectively projecting into said slot and maintaining ori-
entation of said cylindrical member upon rotation of said
lobe.
